(57) **CLAIM**

The ornamental design for a TV/DVD/cable monitor shelf, as shown and described.

DESCRIPTION

FIG. 1 is a perspective view of a TV/DVD/ cable monitor shelf showing my new design.

FIG. 2 is a front view thereof; and,

FIG. 3 is a perspective view of the TVD/DVD/ cable monitor shelf in use.

The broken lines shown in the figures represent portions of the TV/DVD/cable monitor shelf that form no part of the claimed design.

1 Claim, 3 Drawing Sheets

FIG. 1

FIG. 2

FIG. 3
